APPARATUS FOR CRYSTALLIZATION
AND THE LIKEIra Merlis, Whitemarsh, Pa., assignor to Acme
Coppersmithing & Machine Company, Oreland,
Pa., a partnership

Application November 6, 1947, Serial No. 784,461

5 Claims. (Cl. 257—79)

1

The invention of which the following is a detailed description relates to novel apparatus for crystallization and the like. In a broad sense the apparatus is adapted for effecting heat transfer whether it be away from or into the material being treated.

In effecting the crystallization of sugar and like material from saturated solutions, the rapidity of the operation is greatly enhanced if some means is provided to overcome the normally poor heat conductivity of the saturated solution. If a saturated solution or liquor containing sugar, organic salts, inorganic salts or like material is subjected solely to cooling or heating effects from the areas surrounding the mass, crystallization occurs very slowly and is localized at first in the areas immediately adjacent to the walls of the container. Moreover, the crystallization is a matter of slow grain growth and the individual crystals are few and large rather than small and many.

In the transfer of heat into a magma of crystals, solution occurs in the same manner by reason of the poor conductivity of the heat into the mass.

It is an object of my invention to provide means for effecting heat transfer uniformly throughout a saturated solution or a loose mass of crystals in order that a finer grained product is obtained uniformly throughout the mass and in a rapid manner.

It is a further object of my invention to hasten the heat transfer effect by rapidly moving the transfer elements through the solution or magma and thus maintain the latter in motion which will bring all of its portions into close proximity to the heat transfer devices.

It is a still further object of my invention to utilize the moving heat transfer devices for speeding up the crystallization by agitation. In this way the initial or seed crystals will be rapidly carried throughout the entire solution and evenly distributed. When combined with the agitation this effects the rapid production of crystals of the desired fineness.

Further objects of my invention will be apparent from the following description of the preferred form of the invention as shown on the accompanying drawings in which

Fig. 1 is a longitudinal vertical section of the heat exchange device taken on the line 1—1 of Fig. 2;

Fig. 2 is a transverse vertical section of the same taken on the line 2—2 of Fig. 1; and

Fig. 3 is a fragmentary transverse section on an enlarged scale of the mode of attachment between the coils and shaft as seen on the plane of Fig. 1.

Briefly described the improved mechanism consists of a tank or similar vessel in which an agitator is rotated. The agitator extends throughout the area within the tank. The agitator is provided with means for circulating a cooling or

heating medium which is thus brought in contact with the entire contents of the tank. The agitator is also provided with sections serving to direct the material longitudinally of the tank and thus promote better heat exchange.

On Fig. 1 I have shown base members 4 which form footings for the tank 5. As shown in Fig. 2, tank 5 has a semi-cylindrical bottom 6 resting upon the base members 4. Ends 7 and 8 are

10 provided for the tank.

Each end of the tank has a central end bearing 9 which is carried within a stuffing box 10.

Centrally disposed in the tank and in alignment with the end bearings is a center bearing 11 mounted upon a cross beam 12.

20 A shaft 13 is carried on the center and end bearings and adapted for rotation. One section of the shaft 13 extends out of the end 7 and carries a large gear 14. On a bracket 15 there is mounted a cross shaft 16 carrying a worm gear 17 enmeshed with the gear 14. The cross shaft 16 has a pulley 18 keyed thereon and driven by a belt 19 or other motive power.

25 The shaft 13 has central passageways 20 in the ends of the sections. The passageway in the section which extends through the end 7 is connected to an inlet pipe 21 by which the heat exchange medium is supplied in either liquid or gaseous form. At the opposite end 8 the corresponding hollow shaft section connects with an outlet 22 for the spent heat exchange medium.

30 Centrally of the shaft and within the bearing 11 the sections also have axial passageways which are in registry.

35 Each section of the shaft 13 carries a heat exchange unit 23. In the form shown each unit consists of a series of interconnected tubular sections or loops 24 which reach from the shaft to within a short distance of the bottom 6 as shown in Fig. 2. The terminal or end portions 25 of the loops 24 are mounted by welding or flanged connections 26 to the shaft in such a manner as to communicate with the hollow passageways in the shaft sections. The intermediate coil portions 27 are bent into right-angular form as shown in Fig. 2. Both the end portions and the intermediate portions have the outer ends bent at a right angle as shown at 28. These bent ends also are turned at an angle to the plane of the right-angled portions. Thus the bent ends of the portions can be brought into registry and fastened by welding or the like.

40 45 The adjacent loops thus joined each form a unit 23. As these units are connected at opposite ends to the shaft sections, this forms a continuous passageway for the circulation of the heat exchange fluid.

50 55 Reinforcing cross bars 30 are mounted at the ends of the loops and form a rigid connection

therebetween. The cross bar is connected by U-bolts 31 to one of the loop sections.

The right-angled coil portions 27 in turn are clamped rigidly against the hollow shaft 13 in the manner shown in Fig. 3. Thus a plate 32 is welded or otherwise engaged to the bend of the coil. A U-bolt 33 fits around the hollow shaft and is welded or otherwise fastened to the latter. The ends of the bolt 33 pass through the plate 32 and thus clamp the latter tightly against the shaft.

In the preferred form I have shown two oppositely directed helical coil sections. They are mounted on the shaft sections on opposite sides of the center bearing 11. They are also directed oppositely so that the agitation given the contents of the tank will be not only circumferential but also inwardly to the center point in the vertical plane of the center bearing. This serves constantly to bring fresh material against the outer walls of the tank and promotes heat exchange by radiation.

When the tank is filled with a saturated solution of crystallizable substance and a cooling fluid pumped through the coils, the fluid cools the coils as it enters from the end 7. The fluid passes through the coils and out through the hollow passages at the center bearing and then traverses the coil loops of the second coil section. Finally the spent cooling fluid is discharged through the outlet 22. By the slow rotation of the agitating loops the material is kept in motion and all parts subjected to the cooling effect.

This results in a uniform cooling effect throughout the solution. Crystallization takes place rapidly and by reason of the agitation the individual crystals are of the desired fineness.

The heat exchange may, however, work in the opposite direction for the purpose of imparting heat rapidly and uniformly to a stiff magma which it is desired to heat in order to reduce its viscosity and facilitate the separation of the crystals from the mother liquor. In this instance the effect of uniform and rapid heating prevents the agglomeration of the crystals.

While I have shown the preferred form of my invention there are many changes in mere details of structure, proportion, and materials which may be carried out without departing from the scope of the invention as defined in the following claims.

What I claim is:

1. Apparatus for heat exchange comprising a tank, bearings in the ends of the tank, a shaft journaled in the bearings, means for rotating the shaft, a plurality of pipes having straight sections bent at their mid portions for attachment to the shaft at the points of bending, the adjacent pipe sections being angularly spaced apart to form a helix and the ends of the pipe sections being connected to form loops, terminal pipes radially mounted on the shaft and connected to the adjacent pipe sections, the shaft ends having axial passageways communicating with the terminal pipe sections and means for conducting a fluid heat exchange medium from end to end of the shaft and through the pipes.

2. Apparatus for heat exchange comprising a tank, bearings in the ends of the tank, a shaft journaled in the bearings, means for rotating the shaft, a plurality of pipes having straight sections bent at their mid portions for attachment to the shaft at the points of bending, the

adjacent pipe sections being angularly spaced apart to form a helix and the ends of the pipe sections being connected to form loops, terminal pipes radially mounted on the shaft and connected to the adjacent pipe sections, means for rigidly connecting the outer ends of the loops, the shaft ends having axial passageways communicating with the terminal pipe sections and means for conducting a fluid heat exchange medium from end to end of the shaft and through the pipes.

3. Apparatus for heat exchange comprising a tank, bearings in the ends of the tank, a shaft journaled in the bearings, means for rotating the shaft, a plurality of pipes having straight sections bent at their mid portions for attachment to the shaft at the points of bending, the adjacent pipe sections being angularly spaced apart to form a helix and the ends of the pipe sections being connected to form loops, terminal pipes radially mounted on the shaft and connected to the adjacent pipe sections, a rigid bar clamped to the outer ends of the loops, the shaft ends having axial passageways communicating with the terminal pipes and means for conducting a fluid heat exchange medium from end to end of the shaft and through the pipes.

4. Apparatus for cooling a solution comprising a tank, bearings in the ends of the tank, a center bearing aligned with said end bearings, a sectional shaft, having one end journaled between the center bearing and each end bearing, means for rotating the shaft, a plurality of pipes having straight sections bent at their mid portions for attachment to each shaft section at the points of bending, the adjacent pipe sections being angularly spaced apart to form a helix and the ends of the pipe sections being connected to form loops, terminal pipes radially mounted on the shaft and connected to the adjacent pipe sections, the ends of the shaft sections having axial passageways communicating with the terminal pipes, the helices of each shaft section being oppositely directed and means for conducting a cooling fluid from end to end of the shaft and through both helices.

5. Apparatus for heat exchange comprising a tank, bearings in the ends of the tank, a shaft journaled in the bearings, means for rotating the shaft, a plurality of pipes having straight sections bent at their mid portions, clamping means for holding said mid portions to the shaft at the points of bending, the adjacent pipe sections being angularly spaced apart to form a helix and the ends of the pipe sections being connected to form loops, terminal pipes radially mounted on the shaft and connected to the adjacent pipe sections, the shaft ends having axial passageways communicating with the terminal pipes and means for conducting a fluid heat exchange medium from end to end of the shaft and through the pipes.
